TOOTH CLEANING DEVICE HAVING
ABSORBENT LAMINATIONSGeorge C. Halford, Jr., Cleveland Heights, Ohio
Application September 22, 1951, Serial No. 247,798

1 Claim. (Cl. 15—223)

1
This invention relates to a device for cleaning the teeth.

The object of the invention is to provide an improved cleaning device which will be extremely effective in cleaning the teeth.

Another object is to provide an improved cleaning device which will effectively apply dentifrice to all surfaces of the teeth.

Another object of the invention is to provide an improved cleaning device which is extremely simple in construction.

Another object is to provide an improved cleaning device which may very economically be manufactured.

Another object is to provide an improved cleaning device which is readily disposable.

Another object is to provide an improved cleaning device which can be used only once.

Other objects will hereinafter appear.

The generally accepted procedure in cleaning teeth consists of taking a small brush with bristles between $\frac{1}{4}$ and $\frac{1}{2}$ inch long at one end, saturating the brush with water, applying a dentifrice to the bristles and then scrubbing the teeth with the bristles, there being several schools of thought as to whether they should be brushed horizontally or vertically, and the like. From time to time the tooth-brusher expectorates mixed saliva, dentifrice, water and foreign particles and he concludes by rinsing his teeth with water, shaking water out of the brush and hanging it over the wash bowl.

This procedure has a number of disadvantages and objectionable features, some of which are recognized and others not.

For instance, if brushes be composed of stiff bristles, they will ride upon the projecting surfaces of the teeth and not reach into the interdental spaces or other recesses, while if the bristles are soft, they tend to bend over in the same direction and mat into a surface composed of the sides of the bristles which, while it produces less abrasive action, slides over the teeth also without penetrating effectively into depressions in and between the teeth.

If the bristles are stiff, they may penetrate the membranous covering of the gums, damaging this membrane and causing bleeding. Damage of the membrane may, in extreme cases, cause recession of the gums and also raises the possibility of infection.

The possibility of infection is aggravated by the fact that the tooth brush is hung in the open between uses and, generally being hung up wet, has every opportunity to collect dust, germs and

the like to produce unsanitary conditions which the dentifrice is supposed to be sufficiently germicidal to offset, but which is not always successfully taken care of in this manner.

Again, brushes are relatively expensive and there are periods when shortages of suitable bristle material have caused the substitution of less desirable bristles and some of the synthetic substitutes have been much more brittle and much more inclined to break, leaving sharp points or edges, than are natural bristles.

Moreover, the use of relatively large quantities of water in rinsing the teeth flushes from them the dentifrice so quickly that any therapeutic value that this material might possess has a negligible opportunity to exert itself.

The present invention eliminates the above-recited disadvantages and others.

It will be better understood from the description of one practical embodiment thereof illustrated in the accompanying drawings, in which:

Figure 1 is an elevational view of the device, showing it in engagement with the incisors of a set of teeth;

Figure 2 is an end elevation of the device of Figure 1;

Figure 3 is a side elevation of the same device;

Figure 4 is a perspective view of the handle or shank of the device of the first three figures; and

Figure 5 is a perspective view of one of the laminations included in the device of the first three figures; and

Figure 6 is a perspective view of a collar which retains the laminations as illustrated in Figure 1 and Figure 3.

The present invention contemplates the provision of a cleaning device which will be used only once and may readily be disposed of after using. It further contemplates such a device which may be easily and economically manufactured of materials which are soluble in, or at least softened by, water and is sufficiently light and small that a relatively large supply of the devices may be kept on hand, each preferably being individually packaged in a sanitary and bacteria-impervious container such as a cellophane envelope.

It requires no water and it reaches into recesses in the teeth effectively but without harsh abrasive action.

The device can further be impregnated with any desired dentifrice and thus eliminates the handling of this material as a separate item.

It makes very effective the use of certain materials, such, for instance, as ammoniated dentifrices, the use of which, with the older type brush,

was extremely unsatisfactory and the benefits of which were largely lost through the material being eliminated from instead of retained in the mouth after cleaning the teeth.

The device in the drawing is shown in unused condition in Figures 2 and 3, and is shown in use in Figure 1.

It consists of a shank or handle 1 which may conveniently be an elongated cylinder of helically or spirally wound paper or other sheet material 10 and held together by a water-soluble adhesive such as glue—it being understood, of course, that a glue of a relatively slow solubility is required so that the device will not disintegrate before the tooth cleaning operation is completed.

This handle or shank as shown is formed at one end into a flange or head 2, which may easily be done as part of or in conjunction with the operation of winding the handle.

Slid onto the handle are a series of serrated or star-shaped discs or laminations 3 each having a central aperture which closely fits the handle or shank.

The laminations are preferably secured to the handle by a water soluble glue, and may easily be located by being moved against the head 2.

It will be understood that the actual scrubbing elements above described as the laminations 3 may be formed integrally, in other words, a fluted tubular piece of material might be used, although, in such case, it is preferably cut at least as far down as the bottom of the flutes or serrations by circumferential cuts which provide pointed lugs or tabs corresponding to those which in the laminae (according to Figure 5) are formed by the projecting points.

The actual scrubbing element, whether it be integral or a stack of laminations as above described, is made of a flexible water absorbent material such as felt. Preferably it has a fibrous and somewhat resilient nature, and various animal felts, including wool felt, are very satisfactory for this purpose.

The scrubbing element may further be held in place by a collar 4 of paper or similar material, slid against the inner end of the stack of laminations and secured to the handle by water-soluble adhesive.

With a scrubbing element of the size and proportions shown in the drawing, it is found that the points or serrations thereof easily bend over and adapt themselves to irregularities in the tooth surface, making it possible to scrub this surface very thoroughly and dislodge foreign particles therefrom.

It is possible to impregnate the scrubbing element with any desired dentifrice, either while the material is in sheet form before the laminations are cut from it, or after these have been cut, or even after assembly.

In use, the cleaning device is merely taken from its sanitary envelope and applied directly to the teeth. No water is supplied, but the dentifrice causes the saliva to flow in sufficient quantities to

moisten the device; and this saliva, together with dislodged solid particles, is absorbed in and adheres to the felt, or similar material, so that when the user has gone over his teeth, he has actually removed from them all bacteria, particles of foreign material and the like and takes them from his mouth upon removing the cleaning device, leaving in his mouth and upon his teeth a coating of the dentifrice material.

He has then only to throw away the used cleaning device, which will, if thrown into water, completely disintegrate upon the dissolution of the adhesive holding its various parts together, so that it may easily and safely be disposed of by being thrown into a water closet or similar apparatus.

Experiments made with this cleaning device show that it is very much more effective than the ordinary tooth brush and that its improvement thereover is especially marked with the use of ammoniated dentifrices.

It will be apparent that both the head 2 and collar 4 may be omitted and that this merely requires a little more careful application of the adhesive used to secure the laminae to the handle.

While I have described the illustrated embodiment of my invention in some particularity, obviously many modifications and variations thereof will readily occur to those skilled in the art to which it appertains, and I therefore do not limit myself to the details shown and described, but claim as my invention all such modifications, variations and improvements coming within the scope of the appended claim.

35 I claim:

A tooth cleaning device comprising a handle made of a plurality of convolutions of sheet material secured together by water-soluble adhesive and a series of flexible absorbent tooth-engaging 40 laminae secured to said handle by water-soluble adhesive, said laminae each comprising a disc having peripheral outwardly extending tooth-engaging projections.
